UNITED STATES PATENT OFFICE.

ANDREW J. GALLAHER, OF ST. LOUIS, MISSOURI.

METHOD OF AND APPARATUS FOR HEATING WATER.

Application filed June 28, 1919. Serial No. 307,410.

To all whom it may concern:

Be it known that I, ANDREW J. GALLAHER, a citizen of the United States, residing in the city of St. Louis, in the State of Missouri, have invented a certain new and useful Method of and Apparatus for Heating Water, of which the following is a full, clear, and exact description, such as will enable others skilled in the art to make and

10 use the same.

My invention consists in the method and in the construction and arrangement of parts hereinafter described and particularly pointed out in the claims. In describing the various arrangements employed and shown in the drawings hereto attached and described in the specification I do not limit my invention to the precise form or construction of apparatus shown or the several 20 parts thereto inasmuch as various alterations may be made without changing the scope of my invention. My object is to heat water quickly and economically. My invention may be used in heating water to supply 25 the heating systems in residences and other buildings and likewise in quickly providing hot water for washing and other purposes.

In the drawings, Figure 1 is a side view of my water heater. Figure 2 is a transverse 30 sectional view of the heater taken on the line 2—2 of Figure 1. Figure 3 is a fragmental, longitudinal sectional elevation showing the lower end of the heater. Figure 4 is a sectional, plan view showing the lower end of the heater and connections. Figure 5 is a view somewhat similar to Figure 3 of the upper end of the heater. Figure 6 is a detail, longitudinal sectional elevation showing a burner baffle and its support, and 35 Figure 7 is a plan view of the baffle and its support as shown in Figure 6. In the drawings, 40 4 is the water heater, 5 is the gas burner, which I prefer to use for heating the water. It consists of a pipe or pipes with one or more rows of apertures 6 therein for the outflow of gas. The sections 7, 45 preferably consist of tubes 8 designed to afford large heating surface and headers at the ends thereof. These sections are preferably so arranged that when they are placed 50 in position the outflow header-parts 9 are somewhat higher than the in-flow header-parts 10. For convenience in manufacturing and assembling, I generally make all 55 the sections alike except those forming the side walls. I arrange these sections in three

or more tiers with clear open spaces between them extending preferably from side wall to side wall of the heater, the number of tiers and the number of sections in each tier 60 being determined by the amount of water-heating desired. The tubes 8 may be of other shapes than that of the triangular form shown, but I find this form desirable, as will be hereafter more fully set forth. 65 The header-parts are shown of rectangular form. When more than one section is used in each tier, the adjacent header-parts are united and rendered water-tight by the use of push nipples 11. The sections are held 70 firmly in position both vertically and transversely by bolts as at 25. The headers thus made preferably have a cross-section equal to the aggregate cross-sections of all the tubes of that tier. 75

I prefer to make the bases 12 of the tubes 8 of greater width than the rectangular header-parts and invert alternate sections as shown.

From the upper header of the tier of sections subjected to maximum heat extends the outlet pipe 13. Through this outlet pipe the heated water flows to its point or points of distribution. Though this outlet pipe is shown to extend directly out of the water 80 heater from the header, it is clear that the water flowing from the sections subjected to maximum heat may be made to pass through additional pipes in the water heater before entering an exterior outlet pipe. 14 is a casting containing conduits 15. The conduits here shown extend from the upper header of one tier to the lower header of the tier immediately below. While in Figure 4 this conduit-casting is shown to be 85 separated from the walls of the water heater, it is often desirable to attach this casting directly to the outer wall of the water heater. While I prefer to utilize a single casting for these conduits, yet they 90 may be made separately. These conduits preferably should have a cross-section equal to that of the headers. These conduits 95 preferably should be outside the walls of the water heater. 100

The return flow water is carried to the lower part of the section or tier of sections subjected to minimum heat through a pipe 16 which extends below the base of the section or tier of sections immediately below the former and preferably this return flow 110 pipe extends to a point below the base of the

lowest section. The lower headers of the tier of sections are formed with small apertures 17 so that upon the opening of the cock 18 the water heater may be entirely and 5 conveniently drained. The water space in the headers 10 of the lower tier of sections is connected, by a small aperture 19, with the header of the tier above and the same aperture is provided in the headers above. 10 From the upper part of the uppermost header a small conduit 20 extends into the outlet pipe or expansion tank for the escape of water vapors and air.

In my method of water heating, when 15 heat is applied to the section or tier of sections nearest the source of heat, the warmer water will rise to the upper header and thence flow to a point or points of distribution. While the warmer water is rising to 20 the upper header of this section or tier of sections, the warmer water in each of the other sections or tier of sections is likewise rising to the upper headers thereof. The water which flows into the outlet pipe is re- 25 placed by water which flows by gravity through the conduit 15 from the header above to the lower header of the section or sections nearest the source of heat and a similar flow takes place in the headers and 30 conduits above. The water flowing from the uppermost header is replaced by water from the return flow pipe. This return flow water has been carried in this return flow pipe to a point lower than the base of 35 the section below that section entered by the return flow pipe. By so providing for the flow of the water, the possibility of a reverse flow is prevented and the maximum efficiency of the water heater obtained. By 40 my invention the cool return flow water is brought in contact with the cooler combustion gases and gradually carried through the combustion gases and subjected to increasing temperatures until the water passes 45 through the sections subjected to maximum heat, whereupon the water is returned to the point or points of distribution.

In Figure 2 is shown the arrangement of tubes. The gas burners are supplied with 50 air which passes through the small spaces between the burners 5 and the baffles 21. These baffles are preferably metal although any fireproof material may be used. I prefer them to have flanges as shown. The baffles 55 quickly become heated when the gas is burning and thus the air immediately below the baffles is in turn heated. This heated air is drawn to the burner and because it is thus heated a higher efficiency is secured. The 60 combustion gases from the burner impinge on the broad base of the tube and dividing pass through the spaces between the tube and the adjacent inverted tubes. These 65 gases having passed about the tube of the lowest or first tier, in turn impinge upon

the base of the tube of the tier above, and in turn upon the tubes in the remaining tiers, and finally pass to the flue 22. Where the apexes of the inverted sections are placed slightly lower than the bases of the 70 non-inverted sections the tendency of the combustion gases to take a direct line to the flue is thus prevented. The condensation caused by perfect combustion and low flue 75 temperature which collects on the tubes will, as may be seen from Figure 2, drip down into the baffles and thence through an aperture in the baffles into a suitable pan or other collector (not shown) which is used to catch the drippings. It will likewise be seen that 80 these drippings will not fall on the burner and thus interfere with its working.

The side sections 23 are similar to the sections already described except that the 85 tubes are for convenience made of about half the cross-section of the other tubes. On the side of the water heater opposite the conduit casting are provided doors 24. These doors are so arranged that the carbon and other 90 deposits on and between the tubes may be easily removed. These doors swing on hinges and in case of an explosion of gas in the water heater serve as an outlet for the 95 explosive gases.

In describing the intermediate portions of 100 the water tubes as being arranged in tiers I mean that they are disposed in ranks or rows and that the tubes of each rank are in a zone bounded by substantially parallel planes, and that between the tiers of tubes 105 are clear open spaces extending from side to side of the heater, in which spaces may be manipulated the tools employed for cleaning the tubes of accumulations of soot and ash. The polygonal cross sectional shape 110 of the tubes permits the bounding surfaces of a tier to be in an approximate plane, which is of advantage for structural reasons and to afford facility in the cleaning operations.

The gas burners 5 are located quite close to the lower tier of tubes 8 and opposite to the flat under surfaces thereof in order that the flames issuing from the burners shall be caused to impinge directly against and practically centrally of the tubes. The result of 115 this arrangement, which is highly efficient for heating, is that the heat produced by the flames is strongly reflected from the tubes, and it has been my experience that when ordinary pipe burners 5 are used without baffle plates they soon become clogged with carbon, because they become too highly heated owing to the reflection of heat from the under surfaces of the tubes 8. Such deposit of carbon soon impairs the efficiency 120 of the burner and requires it to be cleaned. When, however, the baffle plates arranged as shown, are employed, several important results are obtained, amongst which may be 125

mentioned these: The combustion of the gaseous fuel is rendered more perfect; the air that supports such combustion is so directed that the burners are kept cool; and the air is directed so as to commingle with the gas and cause the flames at most intense combustion to impinge directly and centrally upon the flat faces of the water tubes; with the result that the efficiency of the heater as a whole is very noticeably increased.

While I have shown my invention in a gas water heater, it is obvious that some of the features thereof are applicable to water heaters using coal, oil or other materials for heating. It is likewise evident that my invention is applicable to vertical water heaters as well as horizontal. While my invention is chiefly designed for the purpose of providing heat for buildings it may be advantageously used as an instantaneous water heater to furnish hot water for washing and other purposes. For such use the water pipe from the main is connected up as the return flow pipe 16 above described and the outflow 13 extends to the point of distribution, or the water heater may be connected up with a storage system. The section or sections for this use are preferably made of copper or some other high thermal-conducting metal.

Having described my invention, what I claim is:

1. In a water heater, three or more tiers of inclined hollow sections, said sections having at each end a header portion and having intermediate portions so formed that with certain of said sections inverted a suitable space for combustion gases is provided around each section, a conduit connecting the upper header of one tier of sections to the lower header in a lower tier, a vent pipe to an outlet or expansion tank in the upper header of the top tier, means for admitting the return flow water to an upper section and means for carrying the water subjected to maximum heat toward a point of distribution.

2. In a water heater, hollow sections through which the water circulates arranged in a plurality of tiers, each formed of a plurality of sections, the sections having intermediate tubular portions arranged in zones bounded by substantially parallel planes and headers at their respective ends, the intermediate portions being of polygonal cross sectional shape and arranged to provide suitable spaces about and between them for the passage of gases of combustion, and the said tiers being one above the other with clear open spaces between them extending across the heater from side to side, the sections constituting any tier being connected with each other through the headers.

3. In a water heater, a plurality of tiers of hollow sections through which the water

circulates, with clear open spaces from side to side of the heater between the tiers, the sections having headers at their ends and intermediate hollow or tubular portions that are of triangular cross sectional shape, such intermediate triangular portions being so arranged in the respective tiers that there are spaces between and about them for the free passage of gases of combustion, and the intermediate triangular sections in the respective tiers being so disposed that the bases of the sections in one tier are directly above the spaces between the sections in the tier below, whereby the gases of combustion passing between the sections of one tier impinge upon the bases of the sections in the tier immediately above, and means connecting the sections to cause circulation of water through them.

4. A water heater such as described in claim 2, having formed in the sides of the heater openings located opposite the open spaces between the tiers of tubes, and doors closing the said openings.

5. In a water heater, the combination of hollow sections through which the water circulates formed with headers at their ends and intermediate tubular portions, the sections being arranged in tiers one above the other and the intermediate portions of the sections spaced apart to permit circulation of gases of combustion about them and inclined so that the water being heated in the sections of any tier flows from the lower to the upper headers thereof, and circulating connections between the higher header of each upper tier and the lower header of a tier below it.

6. The combination stated in claim 5 including also flow connections for carrying away the heated water, leading from the upper headers of the tier subject to the highest heat and the water supply connection leading to the lower headers of the tier farthest removed from the source of heat.

7. The combination stated in claim 5 when the circulating connections between the tiers are located outside the path of the products of combustion.

8. The combination stated in claim 5, including a return flow pipe through which the water to be heated is supplied, connected with the lower headers of the upper tier of sections, such return flow pipe passing in its course to a point at least below the level of the tier of sections next to that into which it discharges, whereby the tendency to reverse flow through the said pipe is prevented.

9. In a water heater, the combination with tubular sections through which the water circulates spaced apart to permit the circulation of gases of combustion about them, the lowermost tubular sections having flat under surfaces and being arranged in a tier,

of burners for a gaseous fuel located below and close to the tubular sections, and baffles located adjacent to the burners and arranged to limit and direct the admission of air thereto, the baffles being constructed to cause the directed air to impinge on the gas flames at points above that from which the gas issues from the burners, whereby the flames are directed centrally against the flat faces of the tubular sections of said lower tier, and the burners are kept relatively cool.

10. In a water heater, the combination

with tubular sections through which the water circulates spaced apart to permit the circulation of gases of combustion about them, the lowermost tubular sections having flat under surfaces and being arranged in a tier, of gas burners located below and close to the said tubular sections and baffles on opposite sides of the burners arranged to direct the air supplied to the burners, the baffles being formed with flanges that direct the air to the gas flames at points above where the gas issues from the burners.

ANDREW J. GALLAHER.
